2 Claims. (Cl. 208—30)

The present invention relates to the separation of oil and wax from their mixtures including both the fractionation of waxy oils and of oily waxes.

In one conventional process for separating wax from oil, the wax-oil mixture is chilled to a temperature sufficiently low to crystallize the wax contained in the oil. The precipitated wax is then separated from the oil by high pressure filtration. This type of operation is limited to oils of relatively low viscosity since more viscous oils cannot be filtered successfully in this manner at the temperatures necessary to employ in order to obtain the desired degree of wax removal. This results in only partial dewaxing of lubricating oils.

When waxy oils of higher viscosity are to be dewaxed, this is normally effected by dissolving the waxy oil in a solvent or mixture of solvents at an elevated temperature and then chilling the solution to a temperature sufficiently low to effect precipitation of the wax which is subsequently removed by low pressure or vacuum filtration. The solvents employed are those which show a preferential solubility for oil over wax at the dewaxing temperature such as various mixtures of benzene and acetone, benzene and methyl ethyl ketone, propane, etc. These solvents are very fluid at low temperatures and reduce the viscosity of the oil to such an extent that very low temperatures may be employed, so that oil which is dewaxed by this type of operation may have pour points lower than 0° F.

However, the matrix assumed by the wax when precipitated from the solvents adapted for use in such a process results in a wax cake which is very voluminous and porous. This leads to rapid filtration, but the wax retains a large amount of solvent and dissolved oil and its porosity causes it to wash poorly. Such wax cakes may contain as much as 60 percent or more of oil. This type of operation gives a soft wax cake which cracks badly and such cracking leads to very poor washing.

In normal solvent deoiling or dewaxing procedures it is usually necessary to employ relatively large volumes of diluents if desirable viscosities of the mixture are to be attained. Such a requirement, of course, reduces the efficiency of the wax separation process since it requires handling unduly large volumes of materials and necessitates the use of excessive refrigeration in order to cool the diluents to the required low temperatures. While this is decreased to a certain extent by incremental dilution of the waxy oil mixture with diluent, it nonetheless results in the use of large volumes of diluent (solvent).

It has been the goal of workers in the field of dewaxing to design a process whereby in one or two operations a wax-oil mixture might be completely separated into wax-free oil and oil-free wax. The meager success attending their efforts is seen when one inspects the types of products obtained from the conventional types of operation outlined above. A limited amount of success has been attained by cooling the wax-oil mixture in the absence or substantial absence of an oil solvent to such a temperature that a major amount of the wax has crystallized and thereafter injecting suitable proportions of diluents (solvents). The objective in this particular process is to attain dewaxing temperatures (filtration temperatures) without having the wax set up to a matrix which is essentially immobile or grease-like.

The so-called "delayed injection process" wherein initial

2

injection of solvent is delayed to a point below the crystallization temperature of a majority of the wax, is achieved according to the literature only by the use of slow cooling and of slow stirring during the cooling period. By slow cooling is meant a process in which the rate of cooling is no greater than about 7° F. per hour. It will be immediately apparent to experts in the art of processing waxes that while a desirable end is achieved in the avoidance of a wax matrix, the process is obviously inefficient in requiring the use of slow chilling and slow agitation.

An improvement in the process for the separation of waxes from oils has been found in which the wax-oil mixture is warmed to form a homogeneous phase and then subjected to rapid chilling while being sheared at a high rate of speed in an enclosed heat transfer unit. The use of this particular chilling device enables the so-called "delayed injection" of oil solvent (diluent) which has beneficial effects outlined briefly hereinbefore. With many wax-oil mixtures this process can be used without difficulty and with advantage since it enables the rapid chilling and hence high throughput combined with delayed solvent injection not heretofore found to be possible or practical.

However, as wax is crystallized from an oil, particularly when it is present in amounts in excess of about 50 percent by weight of the mixture and in the substantial absence of any oil solvent, a highly viscous mass results particularly in the period from about the initial crystallization temperature to a temperature approximately 25° below the average melting point of the wax present. Especially in this period, it is necessary in many cases to increase the power input to the rotating blades of the heat transfer unit in order to provide the desired high speed of rotation and at the same time overcome the high viscosity of the oil-wax mixture. This high power input may result in an undesirable degree of heating of the mixture thus reducing the ultimate efficiency of the heat transfer unit whose chief objective is rapid chilling. Consequently, with many oil-wax mixtures, the efficiency of the unit is substantially reduced and optimum performance is not achieved.

It is an object of the present invention to provide an improved process for the separation of waxes from oil. It is a special object of the invention to provide a process for the improved separation of wax from oil which is more efficient than prior known processes. It is a particular object of the present invention to provide a process for the rapid separation of wax from oil wherein initial injection of oil solvent is delayed without previously experienced penalties. Other objects will become apparent during the following detailed description of the invention.

In describing the invention, reference will be made to FIGURE I, showing the type of apparatus required for successful operation of the invention, the FIGURE II, which is a cross-sectional view of the preferred apparatus and to FIGURE III, which is a diagram of a suitable process of steps of this invention.

Now, in accordance with this invention, an improved process of wax separation from oil is effected by rapid chilling of a homogeneous wax-oil solution (mixture) in an enclosed heat transfer unit wherein a film of oil and wax between $\frac{1}{8}$ and 1 inch thick is pumped through the unit while the film is being agitated by rotating scraper blades which are rotating at a speed of about 200-800 r.p.m. and wherein the power input requirement is materially reduced and the degree of cooling in the unit is substantially improved by the presence of 0.05-0.5 volume of water per volume of the oil-wax mixture. The cooling in this unit, aided by the presence of water, is sufficient to crystallize at least a major proportion of the wax present in the mixture after which a sufficient amount of diluent to dissolve the oil present is added and the oil solution is separated from the crystallized wax. In its pre-

ferred version, the essential steps of the wax separation process is carried out to such an extent that the temperature of the wax-oil mixture at the exit of the high shear enclosed heat transfer unit is at least 25° F. below the average melting point of the wax being crystallized. This optimum type of operation is greatly aided by the presence of a minor amount of water recited above.

The presence of the water appears to function in several aspects. First, the viscosity of the oil-wax mixture is drastically reduced by its presence, thus decreasing the power input requirement to attain and maintain a desired speed of rotation of the scraper blades. This is particularly true when the waxy oils or oily waxes are relatively high viscosity mixtures such as residual stocks and low oil content crude waxes. Secondly, because of the reduction in power requirements caused by the presence of water, the heat generated by the power may be reduced to a remarkable extent so that the ultimate cooling of the oil-wax mixture passing through the unit is far greater than if water is omitted. The presence of water has another function later in the process wherein the wax tends at times to stick to metallic surfaces of the apparatus employed. It has been found that water appears to preferentially wet such surfaces and that the sticking of wax thereto is reduced.

The requirement for use of high shear rapid heat transfer in delayed diluent injection wax separation is based upon the wax matrix which results if a wax-oil mixture is rapidly cooled in the presence of substantial proportions of a diluent or solvent. This results in a waxy structure which forms a bulky filter cake. It has been discovered that the advantages of efficient dewaxing processes are made practical by the use of the above-described high shear rapid chilling method, since by this means the objectionable characteristics of the wax-oil solvent matrix are circumvented and solvent injections may be delayed as long as desired.

The desired operation of chilling under a high rate of shear to a point at least about 20° F. below the average melting point of the wax present also overcomes difficulties encountered in this temperature range. It has been observed that the wax passes through an extremely sticky (soft) crystalline phase at temperatures between about the average melting point of the wax and about 20° F. below. At approximately this lower limit, the wax crystal form apparently changes and provides a more or less fluid slurry which is amenable to being pumped and readily transported.

A suitable cooling unit is shown in some detail in FIGURES I and II. This cooling unit includes a chamber 26 formed as a thin annular confined space between the peripheral wall 27 of a cylindrical vessel and a comparatively large core of shaft 28 mounted therein. The core is provided with scrapers 29 which engage the wall 27 and is preferably operated at relatively high speed in a suitable manner as for instance, by an electric motor driven on a shaft extension 30. The speed or rotation of these blades in commercial operation should vary from about 200 to about 800 r.p.m. depending upon the wax-oil mixture being treated and the size of the heat transfer unit. Surrounding and spaced from the wall 27 is a jacket 31 providing an annular space for cooling fluid which may be delivered through a valve controlled inlet 32 at one end and discharged through an outlet 33 at the other end. A pump delivers waxy oil to an inlet 34 at one end of the cooling unit and the cooled and highly sheared mixture is discharged through an outlet 35 at the opposite end. The jacket for the cooling medium is preferably encircled by a layer of insulation 36. The waxy oil mixture, preferably initially in a uni-phase (homogeneous) state, is forced continuously through the unit by the action of a pump and is cooled. It may be required to crystallize a major proportion of the wax present in the mixture and most preferably to a point at least about 20° F. below the average melting point of the wax.

5

The injection of water into the oil-wax mixture may be made prior to or during treatment of the mixture in the rapid heat transfer unit. This may be by means of a line or lines from a source not shown in FIGURES I and II. The water may be injected in one step or incrementally. One of the surprising features is the drastic reduction in viscosity which occurs, apparently only under the high shear treatment being effected upon the oil-wax mixture. For example, the addition of 0.1 volume of water per volume of mixture results in as much as about 8 fold reduction in viscosity of the mixture. Consequently, it has been found that power requirements for rotation of the scraper blades can be drastically reduced under such circumstances.

10

In the cooling unit the temperature of the waxy oil mixture is reduced to a point which is substantially below that at which the wax is soluble in the oil. The extremely rapid rate of cooling obtained in the cooler of FIGURES I and II is brought about by reason of the fact that the originally warm wax-oil mixture is passed through the cooler in a thin confined layer. Thus, only a relatively small quantity of material is in residence therein at any time. The films on the heat transfer wall are continuously removed and rapidly removed from the wall 25 and mixed with the remainder of the mixture in the cooler. This is effected by the rapidly rotating scrapers which rotate at a speed of from about 100 to 800 r.p.m., dependent upon the particular oil-wax mixture being treated. Thus, fresh material, as it were, is continuously 30 being brought into contact with the heat transfer wall and the temperature of the mass within the cooler is rapidly and substantially uniformly lowered to the desired temperature with no substantial portion of the mass being cooled slowly on the one hand, or on the other hand below the temperature ultimately achieved by the mass 35 as a whole.

40

Various other cooling units may be employed providing they have a rate of heat transfer and a shearing device at least substantially equivalent to that obtained in the cooling unit described and shown in FIGURES I and II. In other words, what is required of the cooling unit is that it shall have a rate of cooling sufficiently rapid to enable one to take advantage of the "delayed injection" process (involving the initial pressure of no more than a minor proportion of diluent) while at the same time the disadvantage of slow cooling with slow agitation is avoided.

45

In the foregoing, reference has been made to a "thin confined layer." The word "thin" is to be interpreted as relative to the diameter of the chamber of the heat transfer surface. Ordinarily the thickness of the layer to be agitated should not be over about 15 percent of the diameter of the heat transfer wall. For instance, a 10-inch diameter chamber might have an 8½-inch shaft or core, leaving an annular space for a ¾-inch thick layer. Thus 50 there is provided a large surface-to-volume ratio. This space may vary from about ½-inch to about 3 inches in thickness consistent with these observations.

55

In addition to scraper blades as shown in FIGURES I and II, the apparatus may contain, if desired, a non-scraping blade provided with a small clearance (1/64-1/4 inch) to cause a breaking down of any gel structure which tends to form between the oil and wax. This results in a more fluid mixture.

60

It will be understood that the layer of oil-wax mixture referred to here also includes the minor amounts of water added as described hereinbefore.

65

In carrying out the process of the invention an essentially single phase, homogeneous mixture (solution) of the wax and oil is first formed. The requirements for this will depend at least in part on the proportions of the wax and oil components. Where the wax is at relatively low concentration, the mixture may already be in homogeneous form, that is, the wax is in solution in the oil. If, however, the wax is present in amounts over approximately 20 percent by weight of the mixture it may be

70

75

necessary to warm the mixture to such a point that a single phase is formed and in which it can be said that the wax is dissolved in the oil or at least forms a homogeneous phase therewith.

The amount of water to be added to the oil-wax mixture may be incorporated therein either prior to or during the warming of the mixture to create a homogeneous wax-oil phase.

The success of delayed solvent injection depends upon the cooling of this homogeneous wax-oil mixture to such a point and under such conditions that a major proportion of the wax is crystallized in a separate phase before sufficient diluent is injected into the mixture to provide it with a relatively fluid (non-plastic) body. Thus, while it is preferred that this initial agitated rapid cooling be conducted in the absence of any diluent, it is also possible with some stocks which may require it to conduct the rapid agitated cooling in the presence of a limited amount of diluent sufficient to reduce the viscosity of the wax-oil mixture but insufficient in amount to maintain the wax-oil fluid at the dewaxing temperature in the absence of rapid agitation. The precise amount which will meet this limitation will vary, of course, from one wax-oil mixture to another.

The rate at which the wax-oil mixture is cooled is far greater than that previously employed in delayed diluent injection processes. Normally this cooling will be in the order of from about 1 to about 40° F. per minute, preferably 3-20° F. per minute.

Following rapid high shear cooling of the wax-oil mixture to such a point that at least a major proportion of the wax present is in crystalline form, the initial injection of diluent is made (unless a limited amount of diluent as referred to hereinbefore was added prior to or during high shear chilling). The diluent may be chosen from any one of a number of diluents (solvents) known in the art of wax-oil separation. They may be single diluents such as aliphatic ketones (methyl ethyl ketone, methyl isobutyl ketone, methyl isopropyl ketone, etc.) or mixtures thereof with aromatic hydrocarbons (benzene, toluene, xylenes, etc.) of liquefied normally gaseous hydrocarbons such as propane or other combinations of these or other well-known dewaxing diluents. The addition of fractional amounts of the dewaxing (deoiling) diluent to the mixture emerging from the high shear chiller results in a sharp drop in viscosity, thus enabling ready transportation of the mixture through further chilling devices and transportation to filters or centrifuges thereafter.

In its preferred form, the diluent is added in a series of stages as the temperature is further decreased rather than adding the diluent all in one stage. This is to be referred to as "incremental dilution" as opposed to single-stage dilution such as is used in many prior art processes. The use of incremental dilution has a two-fold advantage in that there is a smaller total diluent requirement as compared with single-stage dilution. At the same time, the load on the apparatus in volumes of material being transported is correspondingly reduced at each stage. Thus, while a single stage of diluent may be employed (in amounts from about 2 to about 6 volumes of diluent per volume of wax-oil mixture) it is preferred and more efficient to utilize two or more stages of incremental dilution of the oil-wax mixture.

Preferably, the initial dilution (prior to or subsequent to passage through the high shear chiller) is in the order of 0.3-0.75 volume of diluent per volume of wax-oil mixture. Thereafter two or more increments of diluent may be injected preferably in a total of 3-6 increments as the temperature is decreased from the temperature as it emerges from the high shear chiller to the filtration temperature. The overall result of this will be that delayed solvent injection enables the production in an efficient manner and at high throughput of a relatively mobile wax-oil mixture in the virtual absence of any diluent

followed by reduced diluent requirement when employed in the incremental dilution technique.

The mixture proceeds from the high shear chiller through one or more additional high shear chillers or through a series of other chillers normally referred to as double pipe chillers. A double pipe chiller involves a pair of pipes one inside of another and scraper blades or their near equivalents are or may be present. The essential difference between this type of chiller and the high shear type previously described lies in the lack of high speed of rotation of the rotating blades within the double pipe chillers. The blades are present in the latter primarily to advance the flow of the material therethrough and not for providing any appreciable or effective means of shear upon the contents being so treated. Solvent injection may be effected before, during or after passage of the oil-wax mixture through the double pipe chiller.

The mixture is finally cooled to a filtration temperature which is chosen as being optimum for the particular mixture of wax and oil being treated and is then passed to a suitable separation means which may be conveniently a filter or a centrifuge.

In the operation of the high shear rapid heat transfer unit, the rate of heat transfer varies sharply with speed of rotation of the scrapers at relatively low speeds. Thus, between 100 and about 200 r.p.m., the rate of heat transfer approximately doubles at the higher rate. However, between about 200 r.p.m. and up to practical speeds in the order of 800 r.p.m. the rate of heat transfer does not appear to be affected to any appreciable degree by the speed of rotation as long as the wax-oil slurry is reasonably fluid. If, however, the wax-oil slurry is of a relatively viscous character (such as at high wax contents) then the speed of rotation becomes a major factor in determining the change in temperature which may be effected by this apparatus without resorting to modifying means for reducing this factor.

It has been found that if the oil content is below about 15 percent, the speed of rotation becomes an important contributing factor as far as heat input to the highly viscous mixture is concerned. This effect is especially apparent at relatively slow speeds in the order of 100 r.p.m. If the oil content, however, is increased to above 15 percent and preferably 15-25 percent by weight based on the oil-wax mixture, the speed of rotation does not become a major concern since at reasonable speeds the degree of cooling is approximately the same for any rate of rotation.

The addition of water within the recited ranges enables the use of much higher speeds of rotation of the scraper blades without encountering the penalty of heat build-up because of power input for rotation of these blades.

The overall heat transfer coefficient of this type of rapid high shear chiller is in the order of 100-500 B.t.u./hr. x ft.² x °F. As compared with this, the double pipe chillers have an overall heat transfer coefficient of about 40 B.t.u./hr. x ft.² x °F. Use of the rapid chilling high shear coolers results in a savings in solvent requirement in the order of 50 percent over ordinary deoiling procedures where solvent is present at all times.

In carrying out a pilot plant scale example of the present process, a crude distillate paraffin wax containing 8 percent oil, obtained in dewaxing a medium viscosity lubricating oil, was utilized. The high shear chilling unit, known commercially as a "Votator," was operated with the blades being rotated at 200 r.p.m., the inlet temperature being 140-156° F. and the outlet temperature being about 103-104° F. In order to maintain a feed throughput rate of 90 lb./hour, a power input of 10.0 amperes was required. However, dilution of the crude wax with 0.1 volume of water reduced the power requirement to 7.5 amperes, a 25 percent reduction.

Utilizing the rapid chiller high shear unit a study

made of the effect of initial solvent injection showed that as the temperature of initial injection is lowered solvent retention and pore volume of the wax filter cake is decreased. The extent of diluent to oil-wax mixture ratio has a powerful effect upon primary filtration rates. At relatively high ratios in the order of 5 or more the rate is relatively unaffected by the temperature of initial injection. However, at the desirably lower ratios of diluent to oil-wax the temperature of initial injection is a sensitive governor upon filtration rates. Desirable rates are obtained by the use of initial injection temperatures in the order of 90-115° F.

After the wax is deposited on a filter surface it is a desirable step to wash the wax cake to displace any adherent oil film. The time required for displacement decreases as the pore volume of the cake decreases until the wax particles are so close together that the resistance to flow offsets the lower solvent retention and an increase in wash time requirements occurs. Hence, it is evident that too low a temperature of initial solvent injection can be harmful in this respect. Consequently, optimum temperatures of solvent injection for waxes from intermediate range lube oil cuts appear to lie in the range of 90-115° F. This temperature also results in a less viscous slurry after addition of solvent than those obtained under other circumstances. This becomes an important factor in that the less viscous slurries lead to reduced pressure drops in subsequent double pipe scraped exchangers even when reduced solvent ratios are employed. Surprisingly enough, increasing the temperature of initial injection above about 115° F. results in a more viscous slurry and under those conditions more diluent may be required.

High shear chillers (one commercially available form of which has the tradename "Votator") may be used in more elaborate processes, two or more chillers following in subsequent steps for the most rapid heat exchange under favorable conditions promoting the use of reduced amounts of dilution to obtain a filterable product.

A suitable process involving the steps of the present invention is illustrated in FIGURE III. A crude wax melting over the general range of 130-137° F. and having an oil content of 8-23 percent is heated in an area 1 to a homogeneous state at about 140° F. Water from a source 1B is injected into the melted mass by means of line 1A just before reaching the rapid chiller 2. This is then conducted to the high shear rapid chiller 2 wherein it is cooled at a high rate of shear (200-800 r.p.m.) to a temperature of 110° F. It is passed through a series of double pipe exchangers or chillers 3 and 4, being reduced therein to a filtration temperature and then sent to the primary filter 5. Fresh solvent is added to the wax cake for the purpose, first, of washing it and then of repulping it for later filtration on secondary filter 6. The repulp filtrate, which comprises fresh solvent only slightly contaminated with oil or soft wax fractions, is recycled and utilized as the diluent throughout the process. According to FIGURE III, it will be seen that this repulp filtrate from a central source 7 is conveyed by means of line 8 and injected incrementally at indicated points along the lines starting with the exit line from the rapid chiller and proceeding through the double pipe chillers or exchangers. A portion of this repulp filtrate is then utilized for washing the filter cake on primary filter 5. The filtrate from this primary filter

is referred to as a "soft wax filtrate" since it contains low melting point waxes and oils. Since this has been reduced to a low filtration temperature, it is efficient to utilize it in a recycle operation as the cooling medium in one or more of the heat exchangers. Hence, the soft wax filtrate may be sent from primary filter 5 to a central collection point 9 and then recycled through one or more of the exchangers or chillers.

The wax-oil mixtures which may be treated according to the process of this invention include both distillate paraffin waxes and residual microcrystalline waxes. The process contemplates both a dewaxing operation, i.e., separation of a minor amount of wax from a major amount of oil as well as deoiling wherein a major amount of wax is separated from a minor amount of oil contamination. Distillate waxes include not only the normal paraffin waxes but also isoparaffins and naphthenic waxes, associated with the normal paraffins. Microcrystalline waxes are often associated with high melting point normal paraffin waxes and may be fractionated in the process of this invention. In a case where waxes of different solubility characteristics are being fractionated in the process of this invention, it will be understood that the wax which is maintained in a fluid or solution state is regarded as the oil component of the wax mixture.

We claim as our invention:

1. A process for the deoiling of a crude petroleum wax containing 7.5-30 percent by weight of oil which comprises warming the mixture to form a homogeneous phase of wax with the oil, adding thereto 0.05-0.25 volume of water per volume of mixture, rapidly chilling the water-containing mixture at a rate in excess of 1° F. per minute in the substantial absence of an oil solvent to a temperature at least about 30° F. below the average melting point of the wax, said cooling being carried out in an enclosed heat exchange unit wherein the water-containing mixture is pumped through the unit in a film $\frac{1}{4}$ - $\frac{3}{4}$ inch thick, the film being agitated by scraper blades rotating at 300-600 r.p.m., the cooling being sufficient to crystallize a major portion of the wax, and thereafter injecting incremental amounts of a cooled oil solvent while the water-containing mixture is being cooled to a filtration temperature and filtering the crystallized wax from the oil solution.

2. A process according to claim 1 wherein the oil solvent is added in 3-6 increments.
